Gilbert Joseph Hoke, Kenmore, N.Y., assignor to Dunlop
Tire and Rubber Corporation, Buffalo, N.Y.

Filed May 14, 1970, Ser. No. 22,968

Term of patent 14 years

Int. Cl. D12—14

U.S. Cl. D90—20

FIG. 1

FIG. 2

FIG. 3

FIG. 4

FIG. 1 is a perspective view of a tire showing my new design.

FIG. 2 is a fragmentary front view showing the tread and shoulders, it being understood that the tread and shoulder design continues uninterruptedly around the peripheral surface of the tire.

FIG. 3 is a side view of the outer side of the tire.

FIG. 4 is a cross-section taken along line 4-4 in FIG. 2, the outer side of the tire being to the left.

The invention is characterized by the design of the tread and shoulders.

I claim:

The ornamental design for a tire, as shown and described.
